UNITED STATES PATENT OFFICE

2,546,127

CIGARETTE HOLDER

Charles E. Lewis, Trail City, S. Dak.

Application January 26, 1944, Serial No. 519,752

3 Claims. (Cl. 131—190)

1

My invention pertains to a cigarette holder.

An object of my invention is to provide a cigarette holder which will firmly retain a cigarette therein.

A further object of my invention is to provide such a holder wherein by simple manual operation the cigarette butt can be made to drop out of the holder.

A further object of my invention is to provide a reamed conical portion at the end of the holder whereby a cigarette will be snugly held thereagainst, and will allow the cigarette to fall out of the same, so that it will not be necessary to remove the cigarette by means of extra tools or the like.

A further object of my invention is to provide a simple arrangement which is neat in appearance, simple in operation, and requires very few parts.

With these and other objects in view, my invention consists in the construction, arrangement, and combination of the various parts of my device, whereby the objects contemplated are attained, as hereinafter more fully set forth, pointed out in my claims, and illustrated in the accompanying drawings, in which:

Figure 1 is a sectional view of the preferred type of holder taken along the longitudinal axis thereof,

Figure 2 is a side elevation of Figure 1,

Figure 3 is a plan view of Figure 2 showing the device after the cigarette butt is removed,

Figure 4 is an enlarged sectional detail view taken along the lines 4—4 of Figure 1, and

Figure 5 is a side elevation of a portion of Figure 1 with the housing 20 being removed, but with the spring 25 shown in position.

My invention contemplates a provision of a cigarette holder in which the cigarette need only be inserted a very short distance, and yet will be firmly supported, with cooperator means for causing the cigarette stub to fall out after it is smoked without requiring the use of any extra tools or devices to remove the same.

I have used the character 10 to designate the body or member of the holder, the character 11 the mouth portion and the character 12 the central opening therein. At the end of the holder I provide a substantially conical depression 13 which communicates with the opening 12, and the cigarette 14 is inserted into the opening 13 so that its end periphery is snugly engaged therein. A button 15 is pivotally attached at 16 to a pair of arms 17 which are pivotally attached at 18 to the member 10. The arms 17 extend

2

downwardly through suitable slots 19 in a metal housing 20 and across the body 10, and are pivotally attached at 21 to the small roller 22. The member 10 includes a cut away portion at 23 for receiving the roller 22, and attached at 24 to a portion of the metal housing 20 is a leaf spring 25 having the curved end 26. Also pivotally attached at 21 are a pair of arms 27 which extend downwardly to the aforesaid pivoting point 21, and extend through the cut out portions or slots 28 in the housing 20, where they then terminate in the arcuate gripping jaws 29. The portions 27 normally are adapted to spring outwardly as shown in Figure 3 when they are released from the sides of the slots 28.

The cigarette is inserted as explained above. The button 15 is then pushed forwardly toward the cigarette, which operation carries the roller 22 to the position shown in Figure 1 and also carries the members 27 in the same direction as that of the roller. This movement of the members 27 causes the jaws 29 to compress against the end periphery of the cigarette whereby it is grasped and held firmly in the holder.

When the cigarette burns down to the desired length, the button 15 is forced toward the end 11 of the holder, which operation carries the roller 22 against the spring tension of the spring portion 26, the roller being shown by the dotted construction in Figure 1. At the same time the members 27 are forced away from the holder with the cut out portions at 28 allowing them to spring apart, whereby the jaws 29 will also spring apart and the cigarette will fall out of the opening since it is then entirely unrestricted.

It will be understood that in the construction shown in Figure 1 the member 10 includes cut out portions to allow the arms 17 to pass downwardly without bending of the arms, such cut out portions extending from the extreme left hand or forward end of the body 10 to the surface 30 at the right as seen in Fig. 5. Even though this end is cut away, the cigarettes will be firmly held by virtue of the firm engagement of the gripping jaws.

Some changes may be made in the construction and arrangement of the parts of my invention without departing from the real spirit and purpose of my invention, and it is my intention to cover by my claims any modified forms of structure or use of mechanical equivalents which may be reasonably included within their scope.

I claim as my invention:

1. A cigarette holder comprising a mouthpiece 55 having a cigarette receiving end portion, said

end portion having a substantially conical depression therein for receiving a cigarette end snugly, means for gripping said cigarette to firmly hold the same, said means including a pair of jaws adapted to snugly engage portions of said cigarette, arms attached to said jaws, other arms pivotally attached to said first-mentioned arms whereby pivotal movement of said other arms will retract said jaws, said other arms being pivotally attached to said mouthpiece, and a button pivotally attached at the upper extremity of said other arms.

2. A cigarette holder comprising a mouthpiece having a cigarette receiving end portion, said end portion having a substantially conical depression therein for receiving a cigarette end snugly, means for gripping said cigarette to firmly hold the same, said means including a pair of jaws adapted to snugly engage portions of said cigarette, arms attached to said jaws, other arms pivotally attached to said first-mentioned arms whereby pivotal movement of said other arms will retract said jaws, said other arms being pivotally attached to said mouthpiece, a button pivotally attached at the upper extremity of said other arms, a roller attached at the lower end of said other arms, and a spring for retaining said roller in selected position.

3. A cigarette holder comprising a mouthpiece having a cigarette receiving end portion, said end portion having a substantially conical depression therein for receiving a cigarette end snugly, means for gripping said cigarette to firmly hold the same, said means including a pair of spring urged jaws adapted to snugly engage portions

5 of said cigarette, arms attached to said jaws, other arms pivotally attached to said first-mentioned arms whereby pivotal movement of said other arms will retract said jaws, said other arms being pivotally attached to said mouthpiece, a button pivotally attached at the upper extremity of said other arms, a roller attached at the lower end of said other arms, a spring for retaining said roller in selected position, said first-mentioned arms being normally spring-urged outwardly, and slots in said mouthpiece receiving said first-mentioned arms whereby inward movement of the first-mentioned arms will cause said jaws to close.

10 15 20 25 30 35 CHARLES E. LEWIS.
